UNITED STATES PATENT OFFICE

JOSEPH KRELL, OF BERLIN-ZEHLENDORF, GERMANY

PRINTING MACHINE

Application filed May 8, 1928, Serial No. 276,144, and in Germany June 14, 1927.

My invention relates to printing machines and more particularly to machines of the type in which an electrical control is provided for the printing mechanism.

5 It is an object of my invention to improve a machine of this type and to this end instead of operating the selective switches of the control directly by the printing plates I connect the mechanism for operating the switches 10 with the drive of the machine and provide means under the control of the printing plates for locking certain switches in their closed position.

In a preferred embodiment of my machine I provide a shaft which is partly controlled by the printing mechanism, and partly by the feeding means of the machine. The shaft extends across the contacting members of all the selective switches and in 20 one of its final positions, locks, and in the other releases the contacting members. Each selective switch is provided with a detent for locking its contacting members when they are engaged with each other, and the detents 25 are under the control of lugs on the printing plates. When the shaft releases the contacting members they become disengaged with the exception of those that are locked by the detents. The shaft cooperates with a prin- 30 cipal switch which it closes when releasing the contact members and current from the switch now flows through the members which are held engaged. At the end of a cycle the shaft is returned to initial position by a part 35 connected with the printing mechanism.

This involves several advantages as compared with the existing machines of this type.

The printing plates no longer perform any switching movements but the selective switches are closed while the printing plates are fed to the printing station and are opened while the machine is moving except those which are locked in their closed position by the printing plates. In this manner 45 stress on the thin printing plates is eliminated and, besides, the selective switches are not opened and closed under current so that arcing is prevented which on account of the small size of the switches is rather trouble- 50 some.

In reducing my invention to practice I connect the selective switches in series with a main switch which is open while the selective switches are being closed and remains open until all selective switches are opened 55 except those which have been locked by suitable lugs on the printing plates. The selective switches are opened at the same time with, or a short time after, the completion of the feeding movement of the printing plates, 60 and the main switch is closed simultaneously with the opening movement of the switches.

I may so time the operation of the selective and main switches that the selective switches are opened earlier than the main 65 switch is closed.

I may provide means for controlling the printing mechanism through the medium of the printing plates which have arrived at the printing station as it is not required for 70 the reasons stated to feed the printing plates with the object of operating the selective switches.

I may so design my machine that the switch- 75 ing levers of the several selective switches which cooperate with lugs of the printing plates are adapted to rock transversely to the feed of the printing plates so that the lugs may be arranged at one or both sides of the plates and more space is available for the lugs 80 than if they are arranged at the ends of the plates, as in the existing plates.

The means for operating the printing mechanism forms no part of the invention and may be designed as desired, for instance, 85 means may be provided for arresting the printing arm when a plate is skipped, or a part of the printing arm may be placed in in- active position under these circumstances.

My invention also relates to the design of the multiple selective switch which is built up from a plurality of switches combined into a unit, the unit supporting the main switch and the mechanisms for controlling the main switch and the selective switches. 90

In the drawings accompanying this specifi- 100 cation an address printing machine according to my invention is illustrated by way of example, but I am not limited to machines of this kind. The machine illustrated by way of ex-

ample is equipped with a guide in which the printing plates are moved to the printing station in succession by a feed slide.

In the drawings,

5 Fig. 1 is a plan view of the machine,
Fig. 2 is a section on the line II—II in
Fig. 1,

10 Figs. 3 to 5 are illustrations of the selective switch unit, drawn to a larger scale,
Fig. 3 being an elevation viewed in the direction of the arrow III, Fig. 1,

15 Fig. 4 being a plan view of the unit, viewed from above, with a printing plate on top, the plate being partly broken away, and Fig. 5
15 being a plan view of the unit, viewed from below as indicated by the arrow V, Fig. 3.

Fig. 5a is a detail showing the left-hand end of the unit, viewed as in Fig. 5,
20 Figs. 6 and 7 are end elevations of the unit, viewed as in Fig. 2,

25 Fig. 8 is an end elevation of the unit, viewed as indicated by the arrow VIII in Fig. 1,
Fig. 9 is an elevation of the unit, viewed as indicated by the arrow IX, Fig. 1,

30 Fig. 9a is a detail showing the right-hand end of the unit as in Fig. 9,
Figs. 10, 11, and 12 are cross sections of the unit on the line X—X, Fig. 9,

35 Fig. 13 is a diagram of connections,
Fig. 14 is a plan view, and

40 Fig. 15 is an end elevation of a printing plate.

Referring now to Figs. 1 and 2, 1 is the table of the machine, 2 is a guide in the table, 3 are printing plates in the guide which are taken from a supply hopper 4, 5 is a feed slide to which reciprocation is imparted by suitable means not shown and described, 7 is the printing station to which the printing plates 3 are fed by the slide 5, 8 is a printing arm for printing from the printing plate which is at the station 7 at the time, 9 is a pin about which the arm 8 is rocking, and 10 is a printing pad in the head of the arm 8 by which the paper at the printing station is forced against the printing plate above which a ribbon is moving. The arrow 11 indicates the direction of the feed stroke of the slide 5 in which it is moving when the printing arm is elevated, being retracted when the arm descends.

45 The electric control of the machine is not shown in detail, an electromagnet being indicated at 12. The control operates so as to print the plate 3 at the station 7 when current is supplied to the electromagnet 12 and not to print the plate when the magnet is without current.

50 13 is a switchboard having a set of push buttons, as many buttons being provided as there may be different lugs on the printing plates.

55 Referring to Figs. 14 and 15, 14 are lugs arranged near the sides of the printing plates 3.

By way of example, I have shown a plate having two lugs 14 near one side.

The multiple switch unit is shown in detail in Figs. 3 to 12. The unit A which is arranged at the printing station 7 comprises a set of selective switches each arranged in a switching compartment constituted by plates 15 of insulating material. The number of the switching compartments is equal to the number of lugs 14 on the printing plates 3. 60 16 and 17 are conductors arranged in each compartment having tongues 16', 17' by which they are connected to line wires 19. 20 is a contact lever pivoted to the conductor 16, 22 is a contact lever pivoted to the conductor 17, and 21 is a spring tending to hold the lever 20 engaged with the lever 22. 16'' is a check at the conductor 16 which limits the stroke of the lever 20. The lever 22 is hook-shaped and adapted to engage an abutment 17' of the conductor 17, 23 is a spring tending to hold the lever 22 in its upper end position, 24 is a block of insulating material on the lever 22, 25 is the horizontal arm of a bell-crank lever which is engaged by the block 24 and fulcrumed in the plates 15, 26 is the vertical arm of the bell-crank lever which extends into a slot 28 in the cover plate 29 of the unit A, the number of slots being equal to that of the switching compartments. 30 is a control shaft extending throughout the unit A which is crescent-shaped in cross section, and its normal position is shown in Fig. 12 in which it locks all the bell-crank levers 25, 26, 100 causing all contact levers 20 and 22 to engage and to close all switches. On the outer end of the shaft 30 which projects beyond the end wall 31 of the unit at the right in Fig. 9 an arm 32 with a latch 33 is secured and 34 is a spring tending to move the shaft 30 so that the arm 32 assumes the position Fig. 6. Normally, however, the arm is retained by a pawl 35 which is pivoted to a bracket on the end wall 31, as shown in Fig. 9a. 36 are springs tending to pull the pawl into its locking position.

37 is a roller at the end of arm 32 which projects into the path of a lug 38 on a rod 39 which is adapted to reciprocate below the table 1 as indicated by the arrow 51, and is fulcrumed to an extension 8' of the printing arm 8, Fig. 2.

41 is an arm on the end of the shaft 30 which projects beyond the opposite end wall 40 of the unit A, 42, 43 are two contact plates which are insulated from each other and the wall 40, Fig. 8, 42' are two brackets on the plate 42, 44 is a contact spring inserted between the brackets 42', 45 is a fixed contact at the contact plate 43, and 46 is a check for the spring 44 on the plate 42.

When the arm 32 is in the position Fig. 7, that is, locked by the pawl 35, the lever 41 is in the position shown in dot-and-dash lines in Fig. 8. In this position the two contacts

44 and 45 are disengaged, but when the arm 32 has been released and is in the position Fig. 6 the lever 41 forces the contact spring against the contact 45 as shown in full lines in Fig. 8, and the main switch 44, 45 is closed. Current is supplied to the two plates 42, 43 by tongues 42", 43".

The upper end of the pawl 35 extends into a slot in the top plate 29 of the unit A and into the path of a pin 47 on a slide 48 extending below the guide 2 and connected with the feed slide 5 at its rear end. In its final position the slide 5 causes the pin 47 to strike the pawl 35 and to move it so as to release the arm 32, Fig. 9.

Referring now to Fig. 13, this diagram shows that there are as many circuits as there are selective switches. If desired the buttons 13 and the selective switches may be subdivided into several groups or a line selecting device may be provided, not shown, so as to increase the number of combinations as to the control of the printing machine.

The operation of my machine is as follows: Assume that the printing arm 8 is in its lower final position to which corresponds the position of the feed slide 5 shown in dotted lines in Fig. 1. With this position of the arm and slide the arm 32 on the shaft 30 in the unit A is in the position indicated in Fig. 7 in which the pawl 35 is in the position shown in Fig. 9a, holding the arm 32 by its latch 33. This corresponds to the position of the shaft 30 in Fig. 12 in which all selective switches are closed, all contact levers 20, 22 being in contact and the arms 26 being in the notches 28. The lever 41 of the main switch is in the dot-and-dash lines position, Fig. 8, and the main switch is consequently open.

When the printing arm 8 is raised the feed slide 5 moves in the direction of the arrow 11, Fig. 1, and pushes another printing plate 3 to the printing station 7 above the unit A, it being assumed that the printing plate has a single lug 14 in the vicinity of its left edge, and that this plate is to be printed. The corresponding button 13' of the switch board 13 is depressed, and, when the printing plate 3 is almost at the printing station and the printing arm 8 is in its upper final position, the pin 47 engages the pawl 35 and moves it into the position Fig. 9. The consequence is that the latch 33 is released and the spring 34 turns the shaft 30 with its arm 32, 41, moving the arm 32 into the position Fig. 6 and arm 41 into the full-lines position Fig. 8, the shaft 30 moving into the position Fig. 10 in the direction of the arrow 50, releasing the bell-crank levers 25, 26 and allowing all levers 22 to move into disengagement with the levers 20 under the action of their springs 23, except that bell-crank lever which is retained by the lug 14 of the printing plate, Fig. 11. In this manner and with the ex-

ception specified all selective switches are opened and as a small rotation of the shaft 30 from the position Fig. 12 to that in Fig. 10 is sufficient for opening the switches, the opening will occur before the arm 41 has closed the main switch 44, 45. When the main switch closes the circuit of the selective switch which has been locked by the lug 14 is closed at the button 13' and the magnet 12 is energized, causing the pad 10 at the printing arm 8 to move into its active position and printing the plate at the station 7.

When the printing arm 8 descends the slide 5 with the rod 48 is returned into the dot-and-dash lines position, Fig. 1, besides, the rod 39 is displaced in the direction of the arrow 51, Fig. 2, and, by the lug 38, moves the arm 32 from the position Fig. 6 into that in Fig. 7, the latch 33 of the arm 32 forcing back the beveled face below the tooth of the pawl 35—which has returned to its locking position under the action of springs 36 as soon as released by the pin 47—and being caught by the pawl immediately. By the return of the arm 32 into the position Fig. 7 the shaft 30 is also returned into the position Fig. 12 in which all selective switches are closed while at the same time the main switch 44, 45 is opened again.

The machine is now ready for another operation. If upon the following upward stroke of the arm 8 a printing plate 3 gets to the printing station 7 which it is not desired to print, all switching circuits will remain open after the arm 32 has been released by the return movement of the pawl 35 under the action of the rod 48 as the switch button in the board 13 which corresponds to that plate, has not been operated.

Means are provided as shown in Figs. 3, 5, and 5a for locking the arm 32 in the position Fig. 7 in which the main switch 44, 45 is opened and all selective switches are closed. For locking the arm 32 in this position and thereby the shaft 30, I provide a horizontal lever 53 at a bracket of the end wall 31 of the unit A, with a handle 54 which is turned from the full-lines to the dot-and-dash lines position, Fig. 5a in which it engages behind the arm 32. This locking of the arm 32 in the position Fig. 7 has the consequence that the tripping device is not operated.

I claim:

1. In a printing machine having printing mechanism, means for feeding printing plates equipped with lugs past said mechanism, a principal switch under the control of said mechanism and said means, and selective switches also under the control of said mechanism and said means, circuits connected with said principal and said selective switches, and a control in the circuit of each selective switch, each selective switch including contact members, and a locking detent under the control of said lugs for 130

holding said members engaged independently of their control by said mechanism and said means.

2. In a printing machine having printing mechanism, means for feeding printing plates equipped with lugs past said mechanism, a principal switch under the control of said mechanism and said means, and selective switches also under the control of said mechanism and said means, circuits connected with said principal and said selective switches, and a control in the circuit of each selective switch, each selective switch including contact members, and a detent pawl arranged 10 transversely with respect to the direction in which said printing plates are fed, said pawl being under the control of said lugs for holding said members engaged independently of their control by said mechanism and 20 said means.

3. In a printing machine having printing mechanism, means for feeding printing plates equipped with lugs past said mechanism, a principal switch under the control of said mechanism and said means, and selective switches also under the control of said mechanism and said means, circuits connected with said principal and said selective switches, and a control in the circuit of each selective switch, a shaft operatively connected with said printing mechanism and said feeding means to control said principal switch, each selective switch including contact members adapted to be controlled by said shaft, and a locking detent under the control of said lugs for holding said members engaged independently of their control by said shaft.

4. In a printing machine having printing mechanism, means for feeding printing plates equipped with lugs past said mechanism, a principal switch under the control of said mechanism and said means, and selective switches also under the control of said mechanism and said means, circuits connected with the principal and selective switches, and a control in the circuit of each selective switch, a shaft operatively connected with said printing mechanism and said feeding means to control said principal switch, means for locking said shaft in the position in which said principal switch is open, means operatively connected with said feeding means for throwing out said locking means, each selective switch including contact members adapted to be controlled by said shaft, and a locking detent under the control of said lugs for holding said members engaged independently of their control by said shaft.

5. In a printing machine having printing mechanism, means for feeding printing plates equipped with lugs past said mechanism, a principal switch under the control of said mechanism and said means, and selective switches also under the control of said

mechanism and said means, circuits connected with said principal and said selective switches, and a control in the circuit of each selective switch, the combination with said principal switch of a shaft operatively connected with said printing mechanism and said feeding means so as to control said switch, and means on said shaft for operating said selective switches, each selective switch including contact members adapted to be controlled by said shaft, and a locking detent under the control of said lugs for holding said members engaged independently of their control by said shaft.

6. In a printing machine having printing mechanism, means for feeding printing plates equipped with lugs past said mechanism, a principal switch under the control of said mechanism and said means, and selective switches also under the control of said mechanism and said means, a shaft operatively connected with said printing mechanism and said feeding means to control said principal switch, selective switches each comprising a pair of conductors, a pair of contacting levers fulcrumed on said conductors, a bell-crank lever under the control of said lugs, means operatively connected with one of said levers for holding said bell-crank lever engaged with said shaft, a cam face on said shaft adapted to engage with said bell-crank lever, means tending to hold said other contacting lever engaged with said first-mentioned lever, and a check limiting the movement of said other lever toward said first-mentioned lever, circuits connected with said principal and selective switches, and a hand control in the circuit of each selective switch.

7. In a printing machine having printing mechanism, means for feeding printing plates equipped with lugs past said mechanism, a principal switch under the control of said mechanism and said means, and selective switches also under the control of said mechanism and said means, circuits connected with said principal and selective switches, a control in the circuit of each selective switch, and means under the control of said lugs for holding said selective switches closed independently of their control by said mechanism and said means, the combination with said principal switch of a shaft operatively connected with said printing mechanism and said feeding means so as to control said switch, means for locking said shaft in a position in which said principal switch is open, means tending to move said shaft into the position in which said switch is closed, and means operatively connected with said feeding means for throwing out said locking means.

8. In a printing machine having printing mechanism, means for feeding printing plates equipped with lugs past said mechanism, a principal switch under the control of said mechanism and said means, and selec-

tive switches also under the control of said mechanism and said means, circuits connected with said principal and said selective switches, a control in the circuit of each selective switch, means under the control of said lugs for holding said selective switches closed independently of the control by said mechanism and said means, a shaft adapted to control said principal switch, means for locking said shaft in a position in which said principal switch is open, means tending to move said switch into the position in which said switch is closed, and means operatively connected with said feeding means for throwing out said locking means, means associated with said printing means for returning said shaft into the position in which said principal switch is open.

9. In a printing machine having printing mechanism, means for feeding printing plates equipped with lugs past said mechanism, a principal switch under the control of said mechanism and said means, and selective switches also under the control of said mechanism and said means, circuits connected with said principal and said selective switches, a control in the circuit of each selective switch, a shaft operatively connected with said mechanism and said means and adapted to control said principal and selective switches, means under the control of said lugs for holding said selective switches closed independently of the control by said mechanism and said means, and manually operated means for locking said shaft in the position in which said principal switch is open.

In testimony whereof I affix my signature.
JOSEPH KRELL.
